(57) CLAIM

The ornamental design for a bell cuff for clothing, as shown and described.

DESCRIPTION

FIG. 1 is a perspective view of the bell cuff for clothing of the present invention;

FIG. 2 is a front elevational view of the embodiment of FIG. 1;

FIG. 3 is a rear elevational view of the embodiment of FIG. 1;

FIG. 4 is a left side elevational view of the embodiment of FIG. 1; and,

FIG. 5 is a right side elevational view of the embodiment of FIG. 1.

The broken line showing of a shoe, in FIGS. 1-5, is for illustrative purposes only and forms no part of the claimed design.

The bell cuff of the present invention has a stylish cutout configuration both at the front and the back with small cutouts at each side.
